UNITED STATES PATENT OFFICE.

FRANK HAGGENJOS, OF ST. LOUIS, MISSOURI.

MOLD FOR MAKING BRASS CASTINGS.

SPECIFICATION forming part of Letters Patent No. 793,068, dated June 27, 1905.

Application filed March 27, 1905. Serial No. 252,195.

To all whom it may concern:

Be it known that I, FRANK HAGGENJOS, a citizen of the United States, residing at St. Louis, in the State of Missouri, have invented 5 certain new and useful Improvements in Molds for Making Brass Castings; and I do declare the following to be a full, clear, and exact description of the invention, such as will enable others skilled in the art to which it appertains 10 to make and use the same, reference being had to the accompanying drawings, and to the letters of reference marked thereon, which form a part of this specification.

My invention relates to improvements in 15 metal molds for making brass castings, and more particularly such a class of castings as are known as "journal-bearings" of all kinds for railroad and all kinds of cars for light and heavy transportation.

20 The objects of my improvements are to broaden the state of the art by the use of valuable experiments that I have made in my effort to cheapen the process and get a better result. In doing so I change the style of 25 the cages and reduce the size of the hard-sand fillings in proportion to the size of the bearing being made. I also find it necessary in the use of certain mixtures of metal to vary the proportion of metal and sand-surface on 30 the casting to hold the evenness of the mixture and prevent segregation in cooling, and I design these features herein embodied to be improvements on my previous patent, No. 783,577, February 28, 1905, in this same branch 35 of the art.

I attain these objects by the mechanism illustrated in the accompanying drawings, in which--

Figure 1 is a perspective view of the metal 40 part of the mold complete opened. Fig. 2 is a cross-sectional view of the mold complete with the hard-sand fillings inserted in their seatings and cut on the center line of the locking-lever pivots. Fig. 3 is a longitudinal 45 sectional view of the mold complete with the hard-sand fillings inserted in their seatings and cut on the center line of the trunnions at each end. Fig. 4 is an inside face view of one of the cages or frames. Fig. 5 is an in-

side face view of the other cage or frame. 50 Fig. 6 is an inside face view of one of the hard-sand fillings. Fig. 7 is an inside face view of the other hard-sand filling.

In all of the views like letters refer to like parts. 55

In this application it is intended to be shown that the body portion A of the mold, as shown in Fig. 1, is identically the same as that in my previous patent referred to above, and it is also supported and rotated in hangers, so 60 as to present either side of the mold up, making it a reversible mold to be filled with the molten metal through the back or bearing side of the mold and hard-sand filling, as desired. 65

The new and improved part of what is shown in this application is the two cages or frames B and C, hinged to the body portion A of the mold, and their hard-sand fillings D and E. 70

By my continued course of experiments in the casting of journal-bearings of these various kinds I find that in some kinds of mixtures of metals the matter of the segregation of the molten metal in cooling is a matter of 75 very vital importance to be overcome in order to get castings even and homogeneous throughout. The fact that the different kinds of metal composing certain mixtures of metal vary in specific gravity and fuse at different 80 degrees of heat makes it not only difficult to get an even mixture of metal in castings, but also a difficult matter to prevent the heavy metal that melts at a low degree of heat from sweating out onto the surface of the mold 85 and into the sand. I find that I am able to overcome these difficulties by reducing the area of the hard-sand-filling surface of the mold and confining it strictly to the bearing-surface and the middle back lettered portion 90 of the box. This is a necessity to get good castings of these mixtures and proves also to be a saving in the use of sand and the labor of making and handling and drying large 95 hard-sand fillings, which is very apparent in a very large output of castings by this process.

Referring to the drawings again, it is very apparent that the sizes of the hard-sand fill-

ings, as shown in Figs. 8 and 9 of my previous patent, referred to above, are greatly reduced, as is shown in this application in Figs. 6 and 7 and in the openings F and G in the 5 cages B and C. Also it is apparent that the cages B and C of this application are less than the cages B and C in proportion to the size of the mold in the previous patent mentioned, and at the same time they are larger in proportion to the size of the mold than the hard-sand fillings shown in Figs. 8 and 9 of that 10 patent. Hence it is apparent that I have reduced the proportionate size of the cages and have simplified the complicated form of the 15 hard-sand fillings. When these cages are once properly fitted to the outer surfaces of the center mold-section A and are hinged thereto, they are more reliable in forming a perfect joint than the hard-sand fillings of the patent, 20 which must vary on their large surfaces and complicated shapes; but these hard-sand fillings D and E of this application are in plain simple form, with plain sloping sides and rounded corners fitting closely against the 25 plain sloping sides of the openings F and G in the cages B and C and are held in by the turn-buttons c^2 and d^2 at each end of the cages, and the cages also are firmly locked to the center section A by the lever clamp or button I, as 30 is shown in Figs. 1 and 2. These hard-sand fillings, though smaller and more simple in form, serve the same purpose and accomplish the same result as those set forth in the previous patent referred to above. Yet while 35 the construction of the cages is entirely different in shape and the fillings are different and cover less of the surface of the casting-cavity I think it necessary to present additional claims to cover what I believe to be new 40 in this application.

I claim—

1. In a mold for making brass castings the cages or frames seated in and hinged to the sides of the center mold-section and provided with hard-sand fillings held in beveled seatings with turn-buttons and a central gate opening into the casting-cavity, as shown and specified. 45
2. In a mold for making brass castings a central mold-section provided with cages or frames seated in it and hinged and locked to its sides and hard-sand fillings inserted in seatings in said cages and held in place with locking-buttons and a central pouring-gate through the filling into the casting-cavity of 50 the mold, as shown and specified.
3. In a mold for making brass castings the combination of the central section provided with seatings for frames or cages, which are hinged thereto and locked or buttoned by turn-buttons, the said frames or cages being provided with seatings for hard-sand fillings, and turn-buttons to hold the said fillings in, and a central pouring-gate through the said filling into the mold-cavity as shown and specified. 55
4. In a mold for making brass castings, the combination of the frames or cages provided with hard-sand fillings seated in them and secured by turn-buttons, the said fillings having gate-openings to the internal cavity of the 70 mold, the said frames or cages seated in and held to a central mold-cavity section by the hinge-lugs and the locking-buttons as shown and described.

In testimony whereof I affix my signature in 75 presence of two witnesses.

FRANK HAGGENJOS.
